CLAIM

The ornamental design for an illuminable Christmas ornament, as shown and described.

DESCRIPTION

FIG. 1 is a front elevation view of an illuminable Christmas ornament showing my new design;

FIG. 2 is a rear elevation view thereof;

FIG. 3 is a left side elevation view thereof;

FIG. 4 is a top plan view thereof;

FIG. 5 is a bottom plan view thereof; and,

FIG. 6 is an isometric view thereof.

The cord shown in FIGS. 3–5 has been shown broken away to indicate indeterminate length.
